DESIGN FOR A BRUSH

Paul C. Scott, Omaha, Nebr.

Application August 25, 1936, Serial No. 64,565

Term of patent 14 years

To all whom it may concern:

Be it known that I, Paul C. Scott, a citizen of the United States and a resident of Omaha, in the county of Douglas and State of Nebraska, have invented a certain new, original, and ornamental Design for a Brush, of which the following is a specification, reference being had to the accompanying drawing, forming part thereof:

I claim:

The ornamental design for a brush as shown.

PAUL C. SCOTT.
